UNITED STATES PATENT OFFICE.

LEWIS J. HEINTZ, OF BUFFALO, NEW YORK.

DESIGN FOR A FINGER-RING.

SPECIFICATION forming part of Design No. 14,406, dated November 13, 1883.

Application filed July 5, 1883. Term of patent 3½ years.

To all whom it may concern:

Be it known that I, LEWIS J. HEINTZ, of Buffalo, in the county of Erie and State of New York, have invented and produced a new and original Design for Finger-Rings, of which the following is a specification, reference being had to the accompanying drawings, forming a part thereof.

Figure 1 is a vertical section through line X X, Fig. 2. Fig. 2 is a top view, and Fig. 3 represents a perspective view of the ring with the initial left off.

My invention relates to a design for finger-

rings; and it consists of the oval-shaped depression *a*, having an initial letter, *a⁴*, arranged therein, as shown, whereby the general appearance of the ring is greatly improved.

I claim as my invention—

In a design for a finger-ring setting, the oval-shaped concave depression having an initial letter seated therein, as shown and described.

LEWIS J. HEINTZ.
